FILTER BAG ATTACHING MEANS FOR DUST
ARRESTING APPARATUS

Richard Ruemelin, Milwaukee, Wis.

Application September 24, 1949, Serial No. 117,556

2 Claims. (Cl. 183—51)

1

This invention relates to improvements in filter bag attaching means for dust arresting apparatus.

Dust arresting devices as commonly constructed include a collecting box into which the dust-laden air is blown, and a plurality of filter bags having their lower ends communicating with openings in the top wall of said box. During use, the heavy particles of matter in the air readily settle in the collector box, and the finer particles of dust pass up into the filter bags and are deposited on the inner side of the cloth. This dust within the bags is periodically shaken down into the collector box, usually by a mechanical shaking device.

It has, heretofore, been common practice to clamp the lower ends of the filter bags around collars which surround the top openings in the collector box and which project upwardly therefrom, and these collars, being numerous and close together, render the task of cleaning the top side of the collector box very difficult. The spaces between collars are narrow and relatively inaccessible, and the dust can not be swept into the collector box openings because the collars interfere. This clamping method also renders the task of removing the bags relatively difficult. In addition, the formation of the top wall of the collector box with collars materially increases the expense of manufacture.

In Patent No. 2,308,309, issued January 12, 1943, the filter bags are equipped with spaced deformable rings which are engageable both above and below the marginal edges of the openings in the collector box. While this construction operates satisfactorily, it requires the expense of two deformable rings and the construction is such that the cloth of the filter bags adjacent the margins of the openings is not protected as well as might be desired. In addition, with the constructions of this prior patent, it is not always simple to snap the rings into a proper position of engagement.

It is a general object of the present invention to provide improved filter bag attaching means of the general type disclosed in prior Patent No. 2,308,309 in which the construction is simplified to reduce expense of manufacture.

A further object of the invention is to provide a construction as above described in which a single deformable ring may be successfully employed at the lower end of each filter bag, the arrangement being such as to facilitate proper engagement of the lower end of the bag without danger of the ring snapping past its seat.

2

A further object of the invention is to provide a construction as above described wherein there are annular ledges below the openings in the top wall of the collector box which cooperate with said wall to provide seats for the deformable rings, said ledges being of such length as to project inwardly beyond the periphery of the opening in the top wall so that the opening in each annular ledge member is of substantially less diameter than the adjacent opening in the collector box wall.

A further object of the invention is to provide a construction as above described wherein, because of the difference in diameter of an annular ledge opening as compared to the diameter of the adjacent opening in the collector box wall, the cloth of the filter bag is given greater protection against wear from abrasive action thereon.

With the above and other objects in view, the invention consists of the improved filter bag attaching means for dust arresting apparatus, and all its parts and combinations, as set forth in the claims, and all the equivalents thereof.

In the accompanying drawing, illustrating one complete embodiment of the preferred form of the invention, in which the same reference numerals designate the same parts in all the views:

Fig. 1 is a side view of a portion of a dust arrester showing a series of filter bags extending upwardly from a dust collector box;

Fig. 2 is a fragmentary vertical section view on an enlarged scale showing the engagement of the lower end of a filter bag with the opening in the top wall of the collector box;

Fig. 3 is a view similar to Fig. 2 showing a fragment of the bag retaining means on an enlarged scale;

Fig. 4 is a plan view of the deformable ring alone; and

Fig. 5 is a view similar to Fig. 3 showing a modification.

Referring more particularly to the drawing, the numerals 8 designate tubular filter bags formed of suitable textile material which has been specially woven for use in dust arresters. A multiplicity of bags is usually employed with the bags extending in rows in two directions.

The lower ends of the filter bags are connected in registration with openings 9 formed in the top wall of a collector box 10. The upper ends of the bags may be equipped with top expansion rings 11 which maintain said upper ends in substantially circular form. Above the expansion ring, each bag is left with a length of loose material to provide a bag tail 12 which may be

looped over one of the bag hanging hooks 13, the shanks of the bag hanging hooks extending through openings in a flange 14 of a shaking angle member 15, and the upper ends of the shanks being engaged with eyes 16 in hanging bars 17.

During use of this type of device it is common practice to apply reciprocating motion to the shaking angles 15 to cause shaking of the upper ends of the filter bags. This dislodges fine particles of dust which have been deposited on the inner walls of the filter bags and causes said particles to fall back into the collector box, it being understood that in this type of device the dust laden air is blown into the collector box, with the heavier particles being immediately deposited in said box, and with the lighter particles being carried up into the filter bags and being deposited on the inner surfaces of the walls thereof while the air passes through the material from which said walls are made.

After a substantial period of use, a relatively large amount of dust is deposited on the top wall 18 of the collector box exteriorly of the filter bags. Where collars are employed, this dust lodges in the narrow spaces between collars. Thus, when the lower ends of the filter bags are disconnected as is necessary from time to time, it has not been possible, with the type of construction utilizing a collar, to merely sweep the dust into the openings because the collars interfere. With the present invention and with the construction of prior Patent 2,308,309, no external collars are employed, and when it is necessary to clean the top wall 18 of the collector box the lower ends of the filter bags can be disconnected and the dust swept directly into the openings 9.

With the construction of the beforementioned prior patent, more effort was required to disconnect and connect the lower ends of the multiplicity of bags than was desirable because of the fact that two rings are employed, it being difficult to make each ring snap into its proper position.

With the present invention, the lower end of each filter bag has a doubled back portion forming a loop 19 in cross-section. This may be formed by a separate doubled back piece of material 20 stitched to the lower end of each bag as at 21. The material 20 may be of a different nature than the material of the filter bags proper so as to have greater resistance to tearing and cutting and may, if necessary, be reinforced on the outer side, where there is contact with the edges of the openings 9, with leather or any other suitable material.

Confined within the loop 19 at the lower end of each filter bag is a deformable ring 22. In the preferred form of the invention the ring is formed of a coil spring as illustrated in Fig. 4, which spring normally holds itself with considerable tension in a circular condition, the spring, however, being readily deformable by pressure of the hand. The ring 22 is of greater external diameter than the opening 9 in the top wall of the collector box.

In order to form a suitable pocket for the ring and provide a tight seal around the lower end of each bag, an annular ledge forming member 23 is employed, the member being connected by welding or the like, as at 28, to the lower side of the wall 13 around each of the openings 9. The ledge forming member is generally angular in cross-section and includes a portion 24 which is angled downwardly and inwardly to an annular

corner 25, the diameter of the corner portion being greater than the diameter of the hole 9 in the top wall. The other portion 26 of each angular ledge forming member extends substantially horizontally from the annular corner portion 25 and projects inwardly to its marginal edge 27, which marginal edge has a diameter substantially less than the diameter of the hole 9 in the collector box wall.

To connect the lower end of a bag, the ring 22 is deformed to permit its insertion through an opening 9. Due to the fact that the ledge 26 projects inwardly a substantial distance beyond the margin of the opening 9, there is no danger of the ring snapping all the way through past the ledge. Instead, the ring hits the upper surface of the annular ledge 26 and readily snaps into the position shown in Figs. 2 and 3. Due to the angle of the portion 24 of each ledge forming member, the ring 22 wedges itself into sealing position to prevent leakage of dust to the exterior.

By having the marginal edge 27 of each ledge forming member project inwardly a substantial distance from the margin of the hole 9, all of the dust laden air passes upwardly in a circular stream whose diameter is limited to substantially the diameter of the portion 27. Inasmuch as this air stream contains abrasive particles, this arrangement keeps the entering air away from the sides of the filter bag until it has passed upwardly a substantial distance and until its velocity has been reduced to a point where there is less wear on the filter bag.

In the modification of Fig. 5 the annular ledge forming member 23' extends at an oblique angle with respect to the top wall 18 and projects inwardly where it has an opening 27'. At said opening the material is flared angularly outwardly and downwardly as at 30 to provide a skirt portion. It is to be noted that the diameter of the opening 27' is substantially less than the diameter of the hole 9 in the collector box wall just as the marginal edge 27 of the form of the invention of Fig. 3 is of less diameter than the diameter of the hole 9.

With the arrangement of the modification, should the bag be inserted downwardly beyond the annular restricted portion which surrounds the opening 27', then by exerting an upward pull, the flared skirt 30 will guide the ring-equipped lower end of the bag into the position shown by the dot and dash lines in Fig. 5, where, in response to a further pull, it can snap past the annular restricted portion 27' and into proper position in the pocket, as indicated by full lines in Fig. 5.

Various changes and modifications may be made without departing from the spirit of the invention, and all of such changes are contemplated as may come within the scope of the claims.

What I claim is:

1. Attachment means for connecting a vertically extending tubular filter bag to a receptacle comprising a substantially horizontal receptacle wall portion extending transversely of the axis of the filter bag when the latter is attached, said wall portion having an opening therein; a ledge forming member surrounding said opening on the lower face of said wall portion to provide an annular pocket outwardly of the margin of the opening and including an annular portion which projects inwardly toward the axis of the opening in the receptacle wall, said annular por-

tion of the ledge forming member having an opening which is of substantially less diameter than the diameter of the opening of said receptacle wall, said ledge forming member having a portion flared downwardly and outwardly from its opening to provide an annular skirt, and a deformable ring secured to the margin of the filter bag, said ring being normally of greater diameter than the opening of the receptacle wall, and said ring be positionable in said pocket to attach said filter bag to said receptacle.

2. Attachment means for connecting a vertically extending tubular filter bag to a receptacle comprising a substantially horizontal receptacle wall portion extending transversely of the axis of the filter bag when the latter is attached, said wall portion having an opening therein; a ledge forming member surrounding said opening on the lower face of said wall portion to provide an annular pocket outwardly of the margin of the opening and including an annular obliquely extending portion which projects inwardly toward

the axis of the opening in the receptacle wall, said annular portion of the ledge forming member having an opening which is of substantially less diameter than the diameter of the opening of said receptacle wall, said ledge forming member having a portion flared downwardly and outwardly from its opening to provide an annular skirt, and a deformable ring secured to the margin of the filter bag, said ring being normally of greater diameter than the opening of the receptacle wall, and said ring be positionable in said pocket to attach said filter bag to said receptacle.
